Primary Examiner — Keith J Wilson(74) *Attorney, Agent, or Firm* — Cermak Nakajima & McGowan LLP; Tomoko Nakajima(57) **CLAIM**

The ornamental design for a deflector for sprinkler head, as shown and described.

DESCRIPTION

FIG. 1 is a front elevational view of a deflector for sprinkler head showing our new design;

FIG. 2 is a rear elevational view thereof;

FIG. 3 is a left side elevational view thereof;

FIG. 4 is a top plan view thereof;

FIG. 5 is a bottom plan view thereof.

FIG. 6 is a cross-sectional view thereof taken along the line 6-6 shown in FIG. 1; and,

FIG. 7 is a front perspective view thereof.

The broken lines shown in figures are for illustrative purposes only and form no part of the claimed design.

The dash-dot line represents the boundary of the claimed design.

1 Claim, 7 Drawing Sheets(56)
